(57) **CLAIM**

The ornamental design for a portable air conditioner as shown and described.

DESCRIPTION

FIG. 1 is a front elevation view of a portable air conditioner showing a first embodiment of my new design;

FIG. 2 is a left side elevation view thereof;

FIG. 3 is a right side elevation view thereof;

FIG. 4 is a top plan view thereof;

FIG. 5 is a perspective view thereof;

FIG. 6 is a front elevation view of a portable air conditioner showing a second embodiment of my new design;

FIG. 7 is a left side elevation view thereof;

FIG. 8 is a right side elevation view thereof;

FIG. 9 is a top plan view thereof;

FIG. 10 is a perspective view thereof;

FIG. 11 is a front elevation view of a portable air conditioner showing a third embodiment of my new design;

FIG. 12 is a left side elevation view thereof;

FIG. 13 is a right side elevation view thereof;

FIG. 14 is a top plan view thereof;

FIG. 15 is a perspective view thereof;

FIG. 16 is a front elevation view of a portable air conditioner showing a fourth embodiment of my new design;

FIG. 17 is a left side elevation view thereof;

FIG. 18 is a right side elevation view thereof;

FIG. 19 is a top plan view thereof; and,

FIG. 20 is a perspective view thereof.

The broken lines show portions of the portable air conditioner that form no part of the claimed design.
